UNITED STATES PATENT OFFICE.

CLARENCE V. KOZLAY, OF NEW YORK, N. Y., ASSIGNOR TO SIDNEY BLUMENTHAL & CO. INC., OF NEW YORK, N. Y., A CORPORATION OF NEW YORK.

DESIGN FOR A PILE FABRIC.

Application filed February 2, 1925. Serial No. 12,243. Term of patent 7 years.

To all whom it may concern:

Be it known that I, CLARENCE V. KOZLAY, a citizen of the United States, residing at New York, in the county of New York and State of New York, have invented a new, original, and ornamental Design for a Pile Fabric, of which the following is a specification, reference being had to the accompanying drawing, forming part thereof.

My new design for a pile fabric is shown in the accompanying drawing; Figure 1 being a plan view of a piece of pile fabric showing my new design, and Figure 2 being a sectional view of the same fabric taken on the line A—A of Figure 1.

I claim:

The ornamental design for a pile fabric, as shown.

CLARENCE V. KOZLAY.
